UNITED STATES PATENT OFFICE.

ALMYR L. NEWMAN, OF WARWICK, RHODE ISLAND, ASSIGNOR, BY MESNE ASSIGNMENTS, TO A. L. NEWMAN COMPANY, OF CRANSTON, RHODE ISLAND, A CORPORATION OF RHODE ISLAND.

FLEXIBLE AND EXPANSIBLE BRACELET AND THE LIKE.

Application filed September 27, 1924. Serial No. 740,348.

This invention relates to flexible and expandable bands or bracelets for use with wrist-watches, or as other articles of utility and adornment, and consists of improvements in the construction of the same.

One object of the invention is to provide an article of the type specified having closely associated, articulated links adapted to flex in relation to each other and to slide one on another to render the whole band or bracelet expandable to slip over the hand of the wearer.

A particular object of the invention is to provide a band, bracelet or other article of this type in which the links may be readily and conveniently coupled and uncoupled without the use of tools, so that units may be added to or subtracted from the article to alter its length.

Another object of the invention is to provide a construction for the band, bracelet or other article in which the connected elements or links are neatly and smoothly joined to adapt the article to be flexed and expanded without dislocating its parts or disclosing unsightly joints or seams.

Further objects of my improvement are set forth in the following specification which describes a preferred embodiment of the invention as illustrated by the accompanying drawings. In the drawings:

Fig. 1 is a perspective view illustrating my improved band or bracelet flexed in circular shape and contracted with its links abutting;

Fig. 2 is an enlarged plan view of the inner side of the bracelet showing it expanded, and with certain of the links illustrated in section in a horizontal plane to disclose the construction of the connecting means;

Fig. 3 is an enlarged side view of a portion of the expanded bracelet showing some of the links in section in a medial vertical plane;

Fig. 4 is a perspective view of one of the main links of the bracelet shown opposite the connecting-link which couples thereto;

Fig. 5 is a plan view of the sheet-metal blank from which the main link is formed; and

Fig. 6 is a plan view of the blank for the slideable connecting-link.

My improved band or bracelet comprises

outer tubular members or box-like links 2, 55 and inner slideable connecting-links 3 which are normally maintained telescoped within the box-links under the tension of coil-springs 4.

The main links 2 are preferably constructed from sheet-metal, being folded or bent up from blanks 5 of the form shown in Fig. 5, which may be stamped or punched out in a drop-press. The blank 5 consists of a strip of relatively thin metal having a central portion 6 of rectangular shape with lateral extensions or wings 7 formed with their opposite edges slightly tapered for a purpose as later explained. The blank 5 is folded at points indicated by the dotted lines in Fig. 5, the wings 7 being first bent downwardly at right-angles to the central portion 6 to form the sides 8 of the box, as illustrated most clearly in Fig. 4, and then folded inwardly again to form the bottom 9 of the box with the edges butted in a longitudinal seam 10, see Fig. 2.

The ends of the wings 7 of the blank 5 are provided with small ears or tabs 11 projecting from their sides and adapted to be bent upwardly from the bottom of the box, as shown in Figs. 3 and 4, to provide lugs or abutments partly closing the openings at its opposite ends. The blank 5 is also formed with smaller ears or lugs 12 projecting from the marginal edge of the wings 7 and adapted to be folded inwardly from the sides 8 of the box to meet the outer edges of the tabs 11, see Fig. 4. The ears or lugs 12 cooperate with the lugs 11 to provide means for clasping the hooked end of the inner link 3 to the main link 2 in the manner as hereinafter more fully explained.

The inner telescoping link 3 is constructed from a sheet-metal blank 15 of the form shown in Fig. 6. The main portion 16 of the blank 15 is of rectangular outline with relatively narrow wings 17 extending from its sides, and a similar wing 18 at one end. The side wings 17 are rounded off at one end, and slightly beyond the points where they join the main portion 16 of the blank are two oppositely projecting ears or lugs 19. The blank 15 is slotted longitudinally on a medial line to provide a bifurcated structure, the cut or slit 20 extending from one end nearly to the wing 18 at its opposite end.

To form the inner slide-link 3 from the

blank 15 the side-wings 17 and end-wing 18 are bent downwardly at points indicated by the dotted lines in Fig. 6, so that they stand at right angles to the main portion 16 of the blank to form a shallow, inverted box as clearly shown in Fig. 3, and at the right in Fig. 4. The end of the blank having the side-lugs 19 is also bent downwardly to form a sort of hook or catch 21 with the lugs 19 adapted to serve as latches when snapped into place behind the ears or lugs 12 at the end of the main link 2. The method of assembling the links in a band, belt, bracelet or like article is as next explained.

15 The inner slide-links 3 are first completely formed and each is assembled with an outer enclosing link 2 by folding the latter there-around. Before the bottom 9 of the box portion of the main link 2 is folded into place on the under side of the inner link 3 the helical wire spring 4 is placed in position between the downwardly bent end-wing 18 of the link 3 and the upstanding lugs 11 at the left-hand end of the link 2, viewed as 25 shown in Figs. 2 and 3. The spring 4 therefore normally tends to telescope the link 3 within the link 2, while adapting it to be partially withdrawn therefrom with its sides 17 sliding in the openings between the edges 30 of the lugs 11 and sides 8 of the box-link 2, see Fig. 2. It will be obvious, however, that the slide-link 3 cannot be entirely withdrawn from its enclosing link 2 after the parts have once been permanently assembled as described.

35 The hooked end or latch 21 on the link 3 provides for its connection with and disconnection from the next outer link 2 of the bracelet with a clasping and unclasping 40 action so that units may be added to or subtracted from the bracelet at will to alter its length as required to adapt it to fit the wrist of the wearer. To assemble the links in a complete bracelet the units or pairs of 45 outer and inner cooperating elements are joined together in the manner as now explained. The bifurcated latch-end 21 of the inner slide-link 3 which projects from the end of its respective enclosing link 2 is first 50 pinched together between the fingers, as shown in Fig. 4, and one of its lugs or ears 19 is inserted through the opening 22 above the lugs 11 at the end of the next adjacent link 2, the links being canted at substantially 55 right-angles to each other for this purpose as indicated by the positions they assume in Fig. 4. The end-lug 19 may thus be hooked in back of the appropriate side-ear or lug 12 on the box-link 2, and by springing the 60 two legs of the link 3 together, as shown at the right in Fig. 4, the opposite lug 19 can then be slid through the opening 22 in the link 2 and seated in back of the opposite end-ear 12. Figs. 2 and 3 illustrate the relative 65 position of the links when clasped together

in the manner as above explained; it being noted that the bent-down hook 21 on the link 3 abuts the inner side of the end-lugs 11 on the main link 2 to prevent the links from being pulled apart, while the engagement of 70 the side-ears or lugs 12 with the notches 23 formed by the end-lugs 19 holds the link 3 from telescoping within the link 2 with which it is clasped.

75 It will thus be seen that the several units, each consisting of an outer main link and its respective inner telescoping link, may be readily clasped together to form a continuous band, belt, bracelet or other article of the required length. When the article is to be used as a watch-bracelet suitable clasps are attached to its ends to adapt it to be fastened to the loops on the watch. Such a type of clasp is described and illustrated in my application for U. S. Letters Patent 85 filed concurrently herewith, the clasp being a separate invention, but adapted for use with the present bracelet. The present device may also be used as a complete bracelet without the watch, or as a belt, and for any 90 other purpose of utility or adornment. When it is required to alter its length the links may be uncoupled by simply springing together the sides of one of the inner connecting elements 3 and releasing its hook 95 or latch portion 21 from the end of the respective outer link 2 to which it is clasped, in a manner the reverse of the clasping operation. One or more of the units of the article may thus be removed to shorten its 100 length, or, when required, new units may be added to increase its length.

105 The outer or top sides of the links may be etched, engraved or enameled with ornamental designs, or set with brilliants to embellish the artistic effect of the whole. It will also be observed that the attractiveness of the article is enhanced by the fact that its parts are neatly and smoothly joined so that no unsightly seams or joints appear 110 when the band or bracelet is flexed, the tapered ends of the sides of the main links, before referred to, providing for a close relation of the links when the band is bent into a circle as illustrated in Fig. 1. The parts 115 slide smoothly on each other when the bracelet is stretched or extended without revealing any conspicuous broken joints or gaps and the article is therefore particularly neat and finished in appearance under all conditions 120 of use. The springs and other mechanical parts are entirely enclosed and hidden from view, besides being protected from injury or dislocation. Moreover, the mechanical construction of the device is extremely simple 125 and compact and adapted for economical cost of manufacture.

130 While I have herein described and illustrated a preferred embodiment of the invention it is to be understood that modifications

may be made in the construction and arrangement of the parts of the device without departing from the spirit or scope of the appended claims.

5 6. I claim:

1. In a flexible band or bracelet, the combination of outer tubular links having lugs projecting across their open ends at both the sides and bottom thereof, inner connecting-links of bifurcated structure having portions adapted to be sprung into place to engage behind both the lateral and bottom lugs on the main links and with their main portions telescoping within the next adjacent outer links, and springs enclosed within the outer links to act on the inner links to maintain them telescoped to contract the bracelet.

10 2. In a device of the type specified, the combination of a series of outer box-like links having lugs projecting across their open ends, a series of inner slide-links formed with flat portions bent downwardly at their ends and provided with laterally projecting lugs, said flat portions being slotted longitudinally to adapt them to be contracted across their width to engage their lugs with those at the end of the box-links, and springs within the box-links acting on the slide-links to hold them in telescoped relation therein.

15 3. In a device of the type specified, the combination of a series of tubular links having lugs projecting upwardly across the openings at their ends with additional lugs projecting inwardly from the sides of the link at their ends, and connecting-links of bifurcated structure having hooked portions at their ends adapted to hook over the top of the bottom lugs at the ends of the tubular links, said bifurcated links also provided with lugs projecting laterally from said hooked portions to adapt them to snap into place behind the side-lugs of the tubular links when the sides of the connecting-link are pinched together.

20 4. In a device of the type specified, the

combination of box-shaped links having a narrow slot extending part way across the end thereof, and connecting links slotted to provide a bifurcated structure having bent 50 down hooks at the ends of its legs with lugs projecting laterally therefrom, the hooked portion of the connecting link being adapted for insertion through the slot in the box-link when its legs are sprung together whereby the side lugs engage at the ends of the slot to lock the links in clasped relation.

5. In a device of the type specified, the combination of box-shaped links folded from sheet-metal blanks with lugs bent upwardly 60 part way across their open ends and additional lugs bent inwardly from the sides, and bifurcated connecting-links having bent down hooks at one end and side notches adjacent thereto, the legs of the connecting-links being adapted to be sprung together to insert their hooks into place behind the bottom lugs on the box-links with the side-lugs thereof engaging the notches to lock the links in clasped relation.

6. In a device of the type specified, the combination of box-shaped links folded from sheet-metal blanks with lugs bent upwardly from the bottom part way across their open ends and additional lugs bent inwardly from their sides at one end, bifurcated slide-links having bent down portions 70 adapted to hook over the bottom lugs on the box-links with notches on their sides engaged by the side lugs thereof, said slide-links formed with bent down wings at their sides slidable through the openings between the bottom lugs and the sides of the adjacent box-link and also formed with a bent down wing at the end, and springs arranged between the bottom lugs at one end of the box-links and the end wings of the slide-links to normally maintain the links in telescoped relation.

In testimony whereof I affix my signature.

ALMYR L. NEWMAN.
